UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,334,125.

Specification of Letters Patent. Patented Mar. 16, 1920.

Application filed August 12, 1918. Serial No. 249,522.

To all whom it may concern:

Be it known that I, SAMUEL B. WILLIAMS, Jr., a citizen of the United States, residing at Brooklyn in the county of Kings, State 5 of New York, have invented certain new and useful Improvements in Telephone-Exchange Systems, of which the following is a full, clear, concise, and exact description.

This invention relates to telephone 10 exchange systems, and more particularly to systems of the call distributing type in which automatic switches are employed for finding the lines of calling subscribers and extending the circuits of such lines to operators' positions which are at the time available.

In accordance with the present invention the calling telephone lines are extended to the connecting circuits of the operators' positions through the medium of finder circuits. 20 Each finder circuit terminates at one end in the brushes of a finder switch which acts to find the terminals of a calling subscriber's line, and at the other end in the brushes of a selector switch which acts to select an available operator's position and find an idle 25 connecting circuit of that position. The telephone lines are arranged in groups, and the lines of each group are multiply connected with the terminals of a group of 30 finder switches. The finder circuits of each group of finder switches have access through their associated selector switches to the connecting circuits of a plurality of operators' 35 positions, the connecting circuits being multiplied to banks of contact terminals on the selector switches.

In the system of this invention the lines are not provided with line and cutoff relays. 40 Instead, the arrangement is such that one or another of the finder switches that serve each group of lines is constantly rotating, with its brushes successively engaging the terminals of all of the lines of the group. 45 When the terminals of a calling line are engaged, the brushes of the switch are stopped on the terminals of this line, and another finder switch serving the same group of lines is started and continues in rotation, 50 until it finds a calling line, when it is stopped and starts another finder switch, and so on.

One of the objects of the present invention is to provide in connection with such 55 a system as that outlined above an improved

finder circuit and associated apparatus, whereby the frequency with which each line is tested by the hunting finder circuit is increased and the calling time of the calling subscriber is correspondingly reduced; or 60 whereby, conversely, the number of lines in the line group may be increased without increasing the calling time; whereby the reliability of the system with respect to the response of a testing finder circuit to a calling 65 line may be increased; whereby each calling line may be insured the sole use of one of the finder circuits for establishing its connection; and whereby the finder circuit may continue to test for an available 70 operator's position, without commencing its test for a connecting circuit, until an available position is found.

In accomplishing the objects set forth above, the finder circuit is provided with a 75 plurality of branches, two in the present instance, and the finder switch is provided with a corresponding plurality of sets of brushes upon which these branches terminate. The finder switch brushes are permanently mounted in fixed relation to each other on a rotating arm or member of the finder switch, so that they are rotated together and stopped together. When there are two sets of brushes, as in the present instance, they 80 are mounted on the rotatable arm so as simultaneously to engage line terminals diametrically opposite each other on the contact drum or cylinder of the switch. Each of the finder circuit branches extending to the 85 finder switch brushes is equipped with testing apparatus which, when it operates, is effective to control the stopping of the switch and the starting of another finder switch of the group. The testing apparatus 90 associated with each branch in operating also brings about the completion of the connection of the finder circuit with that branch and excludes the finder circuit from connection with the other branch. 100

Inasmuch as the telephone lines served by the finder switch constitute a single group, the result of this arrangement is that in each complete rotation of the finder switch each line of the group is tested twice, 105 in the present instance, once by the testing apparatus associated with the branch extending to one set of brushes, and once by the testing apparatus associated with the branch extending to the other set of brushes. 110

Consequently for a given speed of rotation of the finder switch, the average time which elapses from the moment a calling subscriber takes his telephone receiver from its hook until connection is completed with the terminals of his line is reduced to half, in the present instance, of that which it ordinarily would be. Or, conversely, the size of the line group, or the number of lines in the group, may be doubled without reducing the calling time, as each line in the group is tested twice in each rotation of the switch. Or with the same calling time and the same size of line groups, the speed of rotation of the switch may be half of that which it otherwise would be, a thing which may be found desirable under certain circumstances.

Furthermore, by providing the finder circuit with two branches both of which are brought successively into operative relation with each line of the entire line group the chance of the finder circuit failing to be extended to a calling line is just half of what it otherwise would be. If for any reason one of the testing branches fails to respond to the calling condition of a line as the corresponding brushes pass over the line terminals, as for instance through failure of a brush to engage the contact terminals or failure of the testing relays of that branch to operate, a second test is made a moment later by the passing of the brushes associated with the other branch over the terminals of the calling line. Thus each finder circuit is provided with duplicate testing means, as a consequence of which the operation of the system is made more reliable.

The testing devices associated with the two branches of the finder circuit are so interrelated and so connected with the controlling mechanism of the finder switch, that either device when it operates stops the brushes of the finder switch, and operates finder circuit controlling mechanism that causes the finder circuit to be definitely connected with the branch associated with the testing device which has been actuated, and to be definitely excluded from the other branch until the operator acts to release the connection. Furthermore, the relationship is such that when the brushes of the two branches of the finder circuit both engage the terminals of calling lines at the same instant, a preference is exercised in favor of a certain one of the branches so as to prevent the possibility of the finder circuit becoming connected with two calling lines at the same time. When one or the other of the testing devices has operated to stop the finder switch and bring about the definite connection of the finder circuit with the corresponding branch, both testing devices are withdrawn from operative relation with the finder circuit, and held disconnected until the time when the connection is released.

The selector switch through the medium of which the finder circuit selects an available operator's position and extends the circuit to an idle connecting cord of that position, operates first to select the position, and then to find an idle connecting circuit. In accordance with one of the features of the present invention the organization is such that if the selector switch fails to select an operator's position, as, for instance, through the unavailability of all of the positions, the selector switch is prevented from proceeding to that stage of its movement where an idle connecting circuit is selected, but instead is caused to return immediately and then repeat its operator-selecting movement, the switch continuing to repeat this stage of its movement until one of the operators' positions becomes selectable. In the present embodiment of the invention this is accomplished by providing rehunt controlling mechanism which is made operative to bring about a repetition of the operator-selecting movement of the switch at the conclusion of that stage of the movement, and before the connecting circuit selecting stage of the movement is entered into, and further providing means actuated by the successful selection of an operator's position for preventing the rehunt controlling mechanism from becoming operative. The return and rehunting operation of the selector switch is accomplished through the medium of the finder circuit sequence switch, which is caused to move through its controlling cycle and back into position for starting the operator-selecting movement of the selector switch; and means are provided whereby the sequence switch is enabled to move through its various controlling stages without breaking the connection of the finder circuit with the calling line by way of the particular branch over which the connection has been established, and without altering the guarded condition of the calling line which renders it inaccessible to another hunting finder switch and to calls from other lines.

The preferred form of organization for accomplishing the above and other advantageous results will now be described in detail by reference to the accompanying drawings, in which Figure 1 and Fig. 2 are side and end elevations, respectively partly in section, of the line finder switch; and Figs. 3 and 4 taken together and placed side by side as indicated by the lines extending to their margins, represent diagrammatically as much of a complete circuit organization as is necessary to an understanding of the invention. Fig. 3 shows diagrammatically a finder switch with duplicate sets of brushes, and two of the sets of line terminals with which it is equipped, together with two lines extending from subscribers' stations to these sets of terminals, and to the other apparatus

associated with the lines at the central office; Fig. 3 also shows one finder circuit complete, together with enough of two other finder circuits of the group to indicate the way the 5 circuits are interconnected; and Fig. 4 shows a selector switch, one of the connecting circuits at one of the positions to which the selector switch has access, the operator's circuit at this position, and the springjack of a line with which connection may be completed by inserting the calling plug of the connecting circuit.

Referring to Fig. 1 and Fig. 2, the line 10 finder switch comprises a stationary drum 20 on which the line terminals are mounted, a rotating yoke or pair of arms 92 carrying two sets of brushes for engaging the exposed surfaces of the line terminals on the periphery of the stationary drum, a slip-ring collector 91 through which the brushes are connected with the external circuit, driving mechanism, and two magnets 80 and 83 for controlling the movement of the 15 rotating brush carrying yoke. The above- 20 mentioned parts are mounted upon the supporting frame 90. The stationary terminals are arranged in sets 56, 57, 58 and 59 which are insulatedly mounted on the drum; and as many of these sets of terminals are 25 provided as may be desired. As shown in the drawings, the drum is equipped with 50 sets of terminals. This may be increased to 100 or more sets if desired. The brush carrying yoke 92 is carried upon the rotatable 30 shaft 89, and each arm carries a set of brushes 60, 61, 62, 63 and 70, 71, 72, 73, respectively, the sets of brushes being arranged simultaneously to engage sets of contact terminals at diametrically opposite 35 points on the stationary drum. The shaft 89 also has mounted upon it the collector 91 consisting of a hub of insulating material carrying eight slip-rings, one for each of the brushes of the two sets. Coöperating 40 with the slip-rings are two sets of brushes 64, 65, 66, 67 and 74, 75, 76, 77, respectively, the first mentioned set of brushes being connected by way of the associated slip-rings with the brushes 60, 61, 62 and 63, 45 and the second mentioned set of brushes being connected by way of the associated slip-rings with the brushes 70, 71, 72 and 73. 50

The driving of the brush-carrying yoke 92 is effected by means of a pair of friction 55 disks 79 and 69, the first of which is secured to the shaft 89 and the second of which is carried upon the constantly rotating power shaft 68. These two disks are normally out 60 of engagement. When the motor magnet 80 is energized, the friction disk 79 which is resiliently connected with the driven shaft 89, is magnetically attracted and brought 65 into engagement with the edge of the constantly rotating friction disk 69. The disk 79 and the shaft 89 to which it is attached

are thus caused to rotate as long as the motor magnet 80 is energized. When current ceases to flow through the motor magnet 80, the disk 79 is retracted and the rotation of the shaft 89 with its brush-carrying arms 70 is stopped. To insure the instant stopping of the shaft 89 with its associated parts, a holding magnet 83 is provided for moving a pawl 84 into engagement with the ratchet wheel 78, which is rigidly secured to the 75 shaft 89.

The selector CS, shown on Fig. 4 of the drawing is a power driven switch generally similar to the switch disclosed in Patent 1,123,696 issued January 5, 1915, to Craft 80 & Reynolds. This switch consists of a panel board upon which are mounted banks of stationary terminals to which the movable elements of a number of switches have access. Each of the switches comprises a vertical shaft 37 carrying as many sets 26 of line brushes as there are banks of contact terminals in the panel board. The brushes 18, 19, 20 and 21 of each set are normally held apart by a brush controlling lever 27, 90 so that the brushes are kept out of engagement with the stationary terminals as the brushes are moved up. The upward movement of the sets of brushes is effected by the energization of the up-drive magnet 34, 95 which brings an extension of the brush-carrying rod 37 into engagement with a constantly rotating driving member 36; and the downward movement of the brushes is brought about by the energization of the 100 down-drive magnet 33, which moves the extension of the brush-carrying rod 37 into engagement with a member 35 which is constantly rotating in the reverse direction.

The tripping of a particular set of 105 brushes 26 for engagement with the stationary terminals of the associated contact bank is effected by means of the tripping rod 30 which carries a number of tripping fingers 28, one for each set of brushes. The brush 110 controlling lever 27 of each set of brushes is provided with a rearwardly extending tripping lug 29 which is adapted to coöperate with the associated tripping finger 28. In the normal position of the tripping rod 30 115 the tripping fingers 28 are out of the path of the upward movement of the tripping lugs 29. For each degree of the upward movement of the brush-carrying rod with its associated brush sets a tripping lug 29 for 120 a different set of brushes is brought opposite an associated tripping finger 28. If at the particular instant the brush-carrying elevator reaches this point in its upward movement the tripping rod is rotated, the corresponding finger 28 is swung into engagement with the associated lug 29, so that a 125 continued upward movement of the brush set will cause the tilting of the brush controlling lever 27 of this particular set of 130

brushes. All of the other tripping lugs 29 have moved up either too far or not far enough to be opposite their corresponding tripping fingers 28, so that there is no engagement between these two members of the other sets and therefore only one of the sets of brushes is tripped. The fingers 28 are resiliently attached to the tripping rod 30, so that the finger which is opposite a tripping lug 29 when the rotation of the rod occurs remains in engagement with the lug, while the other fingers swing beyond the line of upward movement of their associated lugs.

The rotation of the tripping rod 30 is effected by the tripping magnet 32 under the control of brush 48 and contact bank 50 at the top of the brush-carrying rod 37. The contact bank 50 is so positioned that in the upward movement of the brush-carrying rod the brush 48 engages the first of the terminals 50 when the tripping lug 29 of the lowest set of brushes is opposite the corresponding tripping finger 28, so that the second of the terminals 50 is engaged when the tripping lug 29 of the second set of brushes from the bottom is opposite its corresponding tripping finger 28; and so on, the last of the terminals 50 being engaged by the brush 48 when the tripping lug 29 of the highest set of brushes on the shaft is opposite its associated tripping finger. The arrangement is also such that the brush 48 has reached the highest of the contacts 50 of the associated bank before the brush sets 26 reach the lowest sets of terminals of their associated banks. Thus the selection of a particular set of brushes for engagement with its contact bank is completed before the contact banks are reached in the upward movement of the switch.

At the top of the brush-carrying rod 37 there is an arm carrying a contact brush which, in the upward movement of the switch, is moved over a commutator 51 and successively engages the segments Y, H and X. The segment Y is engaged when the brush-carrying rod 37 is at the limit of its downward movement; the segment H is engaged as the brush 48 passes beyond the highest of the contacts 50 and before the brush sets 26 engage their respective contact banks; and the segment X is engaged when the brush-carrying rod 37 reaches the limit of its upward movement.

Certain of the circuits of the system are controlled by sequence switches which are designated 100, 200 and 400. These sequence switches may be of the type disclosed in Patent 1,127,808, issued February 9, 1915, to Reynolds & Baldwin. Each consists of an electro-magnetically controlled motor or driving mechanism and a number of associated switch cams. The switch cams associated with the sequence switch 100 are

designated 101 to 103, inclusive; those associated with each of the sequence switches 200 are designated 201 to 235, inclusive; and those associated with each of the sequence switches 400 are designated 401 to 412, inclusive. To each of the contacts associated with the various sequence switch cams are applied certain numerals. These numerals in the case of the cams 101, 201 and 401 indicate the only positions of the associated sequence switch in which these particular contacts are open; the numerals applied to all of the other contacts of each sequence switch indicate the only positions of the particular sequence switch in which the associated contacts are closed. These positions of the various sequence switches, and the stages of operation with which these positions are associated, are as follows:

85

105

In detail the operation of the system of this invention is as follows:

It will be assumed that the sequence switch 200 of the finder circuit F, shown on Fig. 3 of the drawing is standing in position 2. Consequently the finder switch LF has its two sets of brushes 60, 61, 62, 63 and 70, 71, 72, 73 in rotation, the circuit that causes the rotation of the finder switch extending from battery through the motor magnet 80 of the finder switch, sequence switch contact 224 (2), back contact 110 of relay 40, sequence switch contact 223 (2), sequence switch contact 234 (2), back contact of relay 41 and back contact and inner left-hand armature of relay 42 to ground. The flow of current in this circuit keeps the motor magnet 80 energized and the driving disk 69 and the driven disk 79 of the finder switch in engagement.

It will further be assumed that the subscriber at station A takes his telephone receiver from its hook, and that the set of brushes 60, 61, 62, 63 is the first of the two sets to engage the terminals 56, 57, 58, 59 associated with the line extending to station A. When the brushes engage the line ter-

125

130

minals, a circuit is closed which extends from battery by way of finder sequence switch contact 226 (2), winding of relay 45, finder sequence switch contact 229 (2), conductor 11, brush 66 and associated slip-ring of the finder switch LF, finder brush 62 and test terminal 58 of the calling line, conductor 7, and resistance 6 to ground. The operation of relay 45 resulting from the closure of 10 this circuit closes a circuit that extends from battery by way of finder sequence switch contact 222 (2), left-hand winding of relay 40, finder sequence switch contact 221 (2), inner armature and front contact of relay 15 45, finder sequence switch contact 228 (2), conductor 10, through the finder switch to terminal 57 and associated conductor 2 of the calling line, thence through the substation switch and back over limb 1 of the calling 20 line to terminal 56 of the finder switch, through the finder switch to conductor 9 of the finder circuit, finder sequence switch contact 227 (2), outer front contact and armature of relay 45, finder sequence switch contact 220 (2) and right-hand winding of relay 40 to ground. As a result of the closure of 25 this circuit the relay 40 is energized and closes a circuit that extends from battery in parallel branches through the winding of the 30 finder sequence switch motor magnet 200 and the line finder switch holding magnet 83, finder sequence switch contact 225 (2), front contact and armature of relay 40, finder sequence switch contact 223 (2), finder sequence switch contact 234 (2), back contact and armature of relay 41, and back contact and inner left-hand armature of relay 42 to ground. At the same time the energization 35 of the relay 40 opens at its back contact and armature the previously traced circuit over which current heretofore has flowed for energizing the motor magnet 80 of the line finder switch. The line finder switch consequently is stopped with its brushes 60, 61, 40 62, 63 on the terminals of the calling line, the stopping being made positive by the energization of the finder switch holding magnet 83; and the finder sequence switch 200 is energized to cause the movement of the 45 50 sequence switch out of position 2 in which it has been resting.

It may be explained at this point that the finder switch is not stopped by the passage of its brushes over the terminals of lines which 55 have already been connected with, for the reason that establishing connection with the line closes a low resistance path from battery to the test conductor 7 of such line, either by way of resistance 93 of the finder circuit 60 or relay 13 of the connecting cord, through which the connection is established if the line is a calling line, or by way of relay 338 associated with the calling plug 334 if the line is a called line; which low resistance path shunts out and prevents the operation 65

of the relay 45 of the finder circuit of the hunting finder switch, so that this relay does not operate to bring its associated relay 40 into connection with the terminals of such a line.

Of the line finder switches LF serving the group of telephone lines only one is in operation at a time. The other line finder switches of the group either have been appropriated by other calling lines and are in use extending the connections of such lines, or are waiting with their sequence switches 200 in position 1. As soon as the finder switch LF finds and stops upon the terminals of the calling line and causes the movement of the associated sequence switch 200 out of position 2, as described above, the sequence switch of another of the group of finder circuits is moved out of its normal position 1 and into its hunting position 2, and causes the associated finder switch to start rotating. This is accomplished by means of a circuit which is closed from battery by way of the sequence switch motor magnet 200' of the waiting finder circuit, assuming that this is finder circuit F', outer left-hand back contact and armature of associated relay 42', sequence switch contact 202' (1), outer right-hand armature and back contact of relay 42 of the finder circuit F that has just seized the calling line, and contact 203 (3 to 5) of the associated sequence switch to ground. The closure of this circuit causes the sequence switch 200' of finder circuit F' to move to position 2 and close the energizing circuit of the motor magnet 80' of the associated finder switch to start the rotation of that switch. If the finder circuit F' is assumed to be busy, and therefore to have its sequence switch in some position between 6 and 18, at the time the finder switch of finder circuit F seizes the calling line, and at this time the finder circuit F' is idle and has its sequence switch 200' in position 1, then the circuit would be 100 from battery through the motor magnet 200', back contact of relay 42', and contact 202' (1) of finder circuit F', sequence switch contact 202' (6 to 18) of finder circuit F', outer right-hand armature and back contact of relay 42 of finder circuit F, and to ground by way of sequence switch contact 203 (3 to 5) of that finder circuit. Thus the first in order of the finder circuits which is idle is selected and its finder switch started in rotation upon the seizure of a calling line by the finder switch which has been hunting. 110 If, under heavy traffic conditions, all of the other finder circuits are in use when the hunting finder switch seizes a calling line, 120 none of them is in condition to have its sequence switch 200 moved into position 2 to take up the hunt when the hunting switch is stopped and moves its sequence switch out of position 2. To take care of this situation a 130

- series path to ground is closed by way of the sequence switch contacts 204 (6 to 1) of all of the finder circuits, which path is ready to act immediately upon the return of any 5 of the finder sequence switches to normal to move that switch out of position 1, and into position 2 where the rotation of the associated finder switch is started. This path to ground by way of the cams 204 of all of the 10 finder circuit sequence switches in series, also operates to move into position 2 the sequence switch of one of the finder circuits when all of the sequence switches for any reason are standing in their normal or 1 position.
- 15 In the operation of the system, as thus far described, the finder circuit F has seized the calling line of station A and the brushes 60, 61, 62, 63 of the finder switch are resting upon the calling line terminals, the sequence 20 switch 200 of finder circuit F has moved out of position 2, and the sequence switch of finder circuit F' has moved from position 1 to position 2 and has caused the associated finder switch to take up the hunt for calling 25 lines. Upon leaving position 2 the sequence switch 200 of finder circuit F continues to move until it reaches and comes to rest in position 6. In position 6 a circuit is closed that extends from battery to finder sequence 30 switch contact 226 (6), winding of relay 45 and finder sequence switch contact 216 (6) to ground. When, as a result, the relay 45 attracts its armatures, it closes a locking circuit for itself that extends by way of 35 finder sequence switch contact 218 (6 to 7), inner front contact and armature of relay 45, finder sequence switch contact 221 (6 to 8), sequence switch contact 208 (6 to 8), and brush 48 and normal resting contact 49 of 40 the selector switch CS to ground.
- When relay 45 has thus been locked up the operation of testing for an idle operator's position is in readiness to be proceeded with, and a circuit is closed by the relay 45 for 45 moving the finder sequence switch from its waiting position 6 to its operator-testing position 7. This circuit extends from battery by way of the motor magnet 200 and contact 215 (6) of the finder sequence switch, outer front contact and armature of relay 45, and sequence switch contact 220 (6 to 9) to ground. In position 7 of the finder sequence switch a circuit is closed that extends from battery by way of the up-drive magnet 34 50 of the selector switch CS, sequence switch contact 215 (7), outer front contact and armature of relay 45 and sequence switch contact 220 (6 to 9) to ground. As the brush-carrying rod 37 of the selector switch moves 55 up, the operator's test brush 48 successively engages the contact terminals 50 associated with the test wires of the various operators' positions to which the selector switch has access; and at the 60 instant of engagement of the brush 48

with each contact terminal 50 the tripping lug 29 of the set of brushes 26 having access to the connecting circuits of the corresponding operator's position has reached a position where it is opposite the associated tripping finger 28. As will hereinafter be described, the test wire 82 of each operator's position that is busy or otherwise unavailable is grounded. The normal resting contact 49 for the brush 48 is also grounded; 70 and as the test brush 48 is so related to its associated contact terminals that it makes contact with one before breaking with the other, the previously traced circuit controlled by the test brush 48 and including 75 the winding of relay 45 continues closed until the test brush reaches the terminal 50 of an operator's position that is available and therefore has its test wire 82 open. When this occurs the relay 45 is deenergized, and 80 in releasing its armatures, opens at its outer front contact and armature the previously traced energizing circuit of the up-drive magnet 34. It also closes a circuit that extends from battery through the motor magnet 90 and contact 217 (7) of the finder sequence switch, outer back contact and armature of relay 45, and sequence switch contact 220 (6 to 9) to ground. The closure of this circuit causes the finder sequence switch 200 95 to move from position 7 to position 9.

As the finder sequence switch 200 reaches position 8 a circuit is closed that extends from battery through the winding of the trip magnet 32 of the selector switch CS 100 and sequence switch contact 209 (8 to 9) to ground. The selector switch CS is at this moment at rest, the energizing circuit of the up-drive magnet 34 having been broken upon the finding of an available operator's 105 position as described. In the present instance it is assumed that the operator's position corresponding with the lowest terminal of the test bank 50 was available, and that therefore the elevator of the selector switch 110 moves upward just far enough to bring the tripping lug 29 of the lowest set of brushes opposite the associated tripping finger 28. Therefore the energization of the tripping magnet 32 as sequence switch 200 reaches 115 position 8 turns the tripping rod 30 and brings the tripping finger 28 associated with the lowest set of brushes 18, 19, 20, 21 into engagement with the corresponding tripping lug 29. The rotation of the tripping rod 30 120 swings all of the other tripping fingers 28 far enough to clear their associated tripping lugs 29 when the upward movement of the brush-carrying rod 37 is resumed. Immediately after the tripping members of the 125 selected set of brushes are brought into engagement a circuit is closed that extends from battery through the up-drive magnet 34, finder sequence switch contact 217 (9), outer back contact and armature of relay 45, 130

and sequence switch contact 220 (6 to 9) to ground. This causes the brushes of the selector switch to resume their upward movement, the brushes of the set whose tripping lug is in engagement with the tripping finger 28 being tripped and made active, and the brushes of the other sets being held apart to clear the terminals of the associated contact banks.

- 10 The selected set of brushes of the selector switch CS is now caused to move over the terminals of the associated contact bank until it finds and is brought to rest upon the terminals of an idle connecting circuit.
- 15 Before describing this, however, it will be well to consider certain of the operations which in the meanwhile are occurring in the operator's circuits of the selected position. Referring to Fig. 4, when the operator is not at her position the telephone plug is withdrawn from the spring jack 195, and the test conductor 82 is connected to ground by way of the switch spring 197 and resting contact of the spring jack 195.
- 20 When the operator is not at her position, the presence of the telephone plug in the spring jack connects the test conductor 82 by way of the switch spring 197 and its alternate contact with battery by way of the winding of the relay 148. When thus connected, no current flows through the conductor 82 when the test brush 48 of the selector switch, which is also connected with battery by way of the test relay 45, engages the corresponding test contact 50. But as soon as the relay 45 of the finder circuit releases its armatures as a result of the interruption of current flow through its circuit, when the test contact 50 connected with battery by way of the winding of relay 148 is engaged, it completes a circuit that extends from battery by way of the winding of relay 148 (see Fig. 4), alternate contact and switch spring 197 of the operator's telephone spring jack, conductor 82, test contact 50 and test brush 48 of the selector switch, finder sequence switch contact 208 (6 to 8), sequence switch contact 221 (6 to 8), inner armature and back contact of relay 45, and sequence switch contact 216 (7 to 8) to ground. Relay 148 in operating closes a locking circuit for itself that extends by way of its right-hand front contact and armature and contact 103 (1 to 17) of the operator's sequence switch to ground. Relay 148 in operating also closes a circuit that extends from battery through the motor magnet and contact 102 (1) of the operator's sequence switch, and the left-hand front contact and armature of relay 148 to ground. The operator's sequence switch thereupon moves out of position 1 and continues to rotate until it reaches and comes to rest in position 18. The locking ground 65 which the relay 148 in operating applies at

its right-hand front contact and armature establishes a grounded condition of the test wire 82 which prevents the selection of this operator's position by any other selector switch; and also provides a circuit for energizing the relay 156 by way of the back contact of relay 157. Relay 156 in operating closes at its front contact and armature a circuit for the illumination of the pilot lamp 167, which notifies the operator that her position has been selected by an incoming call. This locking ground by way of cam 103 of the operator's sequence switch is maintained until just before the operator's sequence switch reaches and comes to rest in position 18. The speed of rotation of the sequence switch 100 is such that before the locking ground is removed by the passing of the sequence switch beyond position 17 another ground is applied to the system of circuits in question by way of conductor 241 and contact 411 (2 to 6) of the listening key sequence switch, as will hereinafter be described.

Returning now to the finding of an idle connecting circuit, as the selected set of brushes of the selector switch CS moves up it successively comes into engagement with the terminals associated with connecting circuits of the selected operator's position. When the connecting circuit is in use, its terminal 25 on the selector switch is connected with battery by way of the right-hand armature and front contact of the connecting circuit relay 95 and one or the other of the two paths controlled at listening key sequence switch cam 408, the relay 95 being energized as long as the connecting circuit is in use. But when the test brush 21 of the selected set of brushes engages the contact terminal 25 of a connecting circuit that is not in use, a circuit is completed that extends from battery by way of finder sequence switch contact 226 (6 to 9), the winding of relay 45, finder sequence switch contact 210 (9), conductor 55, brush 21 and contact terminal 25 of the selector switch, connecting circuit conductor 88, resting contact and switch spring 161 of disconnect key 160, and right-hand armature and back contact of relay 95 to ground. Relay 45 in operating opens at its outer back contact and armature the energizing circuit of the up-drive magnet 34, thus stopping the upward movement of the selector switch 120 brushes. Relay 45 in operating also closes a circuit that extends from battery through the motor magnet and contact 215 (9) of the finder sequence switch, outer front contact and armature of relay 45, and finder sequence switch contact 220 (6 to 9) to ground. The closure of this circuit causes the finder sequence switch to move out of position 9 and to continue to move until it reaches the talking position 17.

In the movement of the finder sequence switch from position 9 to position 17, a circuit is closed that extends from battery through the motor magnet and contact 410 5 (1) of the listening key sequence switch 400 (see Fig. 4), left-hand armature and back contact of relay 95, left-hand back contact and armature of relay 13, back contact and switch spring of relay 81, conductor 87, contact terminal 24 and brush 20 of the selector switch CS, conductor 54, and finder sequence switch contact 212 (11 to 16) to ground. As a result of the closure 10 of this circuit the listening key sequence switch 400 is moved from its normal position 1 to its listening-in position 6. When the sequence switch 400 reaches position 2 a circuit is closed that extends from battery through the winding of relay 13, sequence 15 switch contact 412 (2 to 6), and thence by way of back contact and switch spring of relay 81 to ground at finder sequence switch contact 212 (11 to 16) over the path already traced. When relay 13 operates, it closes at 20 its left-hand front contact and armature a locking path for itself in shunt of its initial energizing path by way of sequence switch contact 412 (2 to 6). When the finder sequence switch passes through position 16 25 and comes to rest in position 17, the energizing path to ground for the relay 13 by way of finder sequence switch contact 212 (11 to 16) is replaced by a path to ground that extends by way of finder sequence switch contact 212 (16 to 17), inner lower armature and back contact of relay 44, finder sequence switch contact 229 (3 to 17), conductor 11, and thence through the line finder switch LF to conductor 7 associated with the calling 30 line, and to ground by way of the resistance coil 6. This circuit is maintained as a holding circuit until the operator acts to release the connection.

When relay 13 operates upon the selection 35 of the connecting circuit, it closes a circuit that extends in parallel branches from battery through the lamps 329 and 335 (see Fig. 4), conductor 255 and lower front contact and right-hand armature of relay 13 to 40 ground. The closure of this circuit causes the illumination of lamp 329 to indicate to the operator the particular connecting circuit to which the call, of which she has been notified by the lighting of her pilot lamp 55 167, is being extended. The lamp 335, however, is not lighted, as it is shunted out by the answering supervisory relay 331, the circuit of which is controlled at the calling subscriber's switchhook in the usual way. 60 Relay 13 in operating also closes a circuit that extends from battery through the winding of relay 95 and to ground by way of the upper front contact and right-hand armature of relay 13. Relay 95 in operating 65 connects, at its right-hand armature, the

test conductor 88 from ground and connects it with battery by way of listening key sequence switch contact 408 (8 to 5) and resistance coil 158. In position 5 to 8 cam 408 of the connecting sequence switch completes 70 the path of test conductor 88 to battery by way of conductor 252 and resistance coil 159, so that the test conductor is connected with battery by way of one or the other of these paths as long as the relay 95 is energized. 75

When the listening key sequence switch 400 moves to its listening-in position 6 as the result of the selection of the connecting circuit, as has been described, it breaks at 80 its cams 403, 404, 405 and 406 the normal connection of the talking conductors 85 and 86 with the conductors 253 and 254, respectively, and connects these conductors in a loop including conductors 236, 237, 238 and 239 through which connection is had with 85 the operator's telephone set and common position apparatus. The operator's telephone set, which is organized in the usual way, is connected with this loop by way of the conductors 244 and 245. The loop includes the ring-back key 184, by means of which the operator is enabled to connect current from the generator 199 back over the circuit for ringing the calling subscriber's bell. In moving to its listening-in position 90 6 the listening key sequence switch also applies ground by way of conductor 241 and contact 411 (2 to 6) to the operator's test conductor 82 and to the energizing circuit including the windings of the relays 148 and 156 of the operator's position. As has been described, this path to ground is closed in 95 the normal operation of the system before the timing sequence switch 100 has passed beyond position 17, so that the operator's 100 position is held continuously unselectable, and the relays 148 and 156 are kept energized from the moment the position is 105 first selected. When the listening key sequence switch reaches position 6 it closes 110 a circuit that extends from battery through the winding of relay 157 (see Fig. 4), conductor 251, sequence switch contact 407 (6) to ground. Relay 157 in operating opens the energizing circuit of relay 156 and releases that relay, thus extinguishing the 115 pilot lamp 167.

The operator may now communicate with the calling subscriber, the talking circuit being closed by way of the cams 403 and 120 405 of the listening key sequence switch 400 now resting in their listening-in position 6 and the cams of the finder sequence switch 200 now resting in their talking position 17. Upon receiving from the calling subscriber the number of the line with which connection is desired, the operator tests the line by touching the tip of the calling plug 334 to the sleeve of the called line jack 339, the spring jack 339 being assumed to be 125 130

connected with a telephone line in the same manner in which the spring jacks 3 and 3' (see Fig. 3) are connected with the lines of stations A and A' and their associated apparatus. If the line is busy the presence of potential upon the sleeve of the spring jack 339 results in a flow of current which acts inductively through the windings of the repeating coil 333 and produces 10 a click in the operator's telephone receiver in a manner well understood in the art. If the called line is free, the insertion of the calling plug 334 closes a circuit that extends from battery through the winding of 15 relay 338, registering sleeve contacts of the calling plug 334 and called line spring jack 339, and to ground by way of the resistance 340. Relay 338 in operating closes a circuit that extends from battery through the 20 calling supervisory lamp 336 and inner front contact and armature of relay 338 to ground. At the same time the energizing circuit of the calling lamp 329 is broken at the outer back contact and armature of relay 338 and that lamp is extinguished. 25 The operator signals the called subscriber by applying ringing current from the generator 199 by means of the ringing key 330 in the usual way. When the called subscriber responds, the calling supervisory relay 332 is energized and extinguishes the calling supervisory lamp 336 by completing a shunt about it.

The operator may now disconnect her 35 telephone set from the connecting circuit, which she does by pressing the listening-out key 187 (see Fig. 4). The pressing of this key closes a circuit that extends from battery through the motor magnet and contact 409 (2 to 6) of the listening key sequence switch 400, conductor 247 and contacts of the listening-out key 187 to ground. This causes the listening key sequence switch to move out of its listening-in position 40 6 and to come to rest in its listening-out position 8, in which position the cams 403, 404, 405 and 406 of the listening key sequence switch act to disconnect the operator's loop conductors 236, 237, 238 and 239 45 from the connecting circuit, and to connect the connecting conductors 85, 86, 253 and 254 directly together for talking purposes. When the listening key sequence switch moves to position 8, as the result of pressing 50 the listening-out key 187, the path to ground by way of listening key sequence contact 411 (2 to 6) is opened, thus clearing operator's position test conductor 82 and rendering the position again selectable. 55 The interruption of the path to ground also deenergizes relay 148; and that relay in releasing closes a circuit that extends from battery through the motor magnet and contact 102 (18) of the operator's sequence switch 100 to ground by way of the left- 60 hand back contact and armature of relay 148. The operator's sequence switch thereupon returns to its normal or 1 position, and is in condition to respond, in the manner already described, to another selection 70 of the operator's position. The movement of the listening key sequence switch out of position 6 also opens, at sequence switch contact 407 (6), the energizing circuit of the relay 157, and that relay in releasing 75 again places relay 156 in readiness to display the pilot lamp 167 upon the selection of the position.

If at any time the operator should have occasion to supervise the connection, she 80 may again bring her telephone into connection with the connecting circuit by pressing the listening-in key 183 (see Fig. 4). This closes a circuit that extends from battery through the motor magnet and contact 409 85 (8) of the listening key sequence switch, contacts of listening-in key 183, conductor 249 and back contact and armature of relay 156 to ground. The listening key sequence switch thereupon moves out of the listening-out position 8, through normal position 1 and into listening-in position 6, being caused to continue to move through position 1 by means of a circuit completed for the motor magnet by way of listening key 90 sequence contact 410 (1), left-hand armature and front contact of relay 95, and upper front contact and right-hand armature of relay 13 to ground. If it should happen that the operator's position has just been selected by an incoming call at the moment that the operator presses the listening-in key 183, the energization of the relay 156 that results from the selection of the position 95 opens the path to ground at the back contact and armature of relay 156, and thus prevents the closure of the listening-in circuit. In this way the operator is prevented from bringing her telephone into communication with an existing connection when it is 100 just about to be connected with another connecting circuit as the result of an incoming call.

When the subscribers hang up their telephone receivers at the end of the conversation, the consequent deenergization of the cord circuit supervisory relays 331 and 332 causes the lighting of the corresponding supervisory lamps 335 and 336. If, before releasing the connection, or at any time 115 during the existence of the connection, the operator wishes to identify the calling line for the purpose of making a charge for the service, she may do so by operating the line identifying key 165 (see Fig. 4),—it being assumed that the listening key sequence switch is at the time in its listening-in position 6. When the key 165 is pressed a 120 circuit is closed that extends from battery through resistance coil 166, contacts of the 125 130

line identifying key 165, conductor 252, listening key sequence switch contact 408 (5 to 8), right-hand front contact and armature of relay 95, contacts 161 of disconnect key 160, conductor 88, terminal 25 and brush 21 of the selector switch CS, finder sequence switch contact 210 (17), outer lower armature and back contact of relay 44, conductor 12, through the line finder switch to conductor 8 associated with the calling line, and thence to ground by way of the lamp 4 mounted on the line lamp board 5. This line lamp board is located within view of all the operators and has a lamp for each of the lines, the arrangement of the lamps being in accordance with the numerical designations of the lines, so that any operator, by making and breaking the contacts of her key 165, and noting the position on the board 5 of the lamp which is flashing, may identify the line connected with the connecting circuit to which her position apparatus is extended. The resistances 158 and 159, one or the other of which is connected in circuit with the lamp 4 as long as the calling line is extended to the connecting circuit, are of relatively high resistance; and the resistance coil 166 associated with the line identifying key 165 is of relatively low resistance. The current flow through the line lamp board is therefore normally insufficient to cause the illumination of the lamp, the lamp being lighted only when the high resistance 159 is shunted by the low resistance 166.

When the operator is informed by the lighting of the cord circuit supervisory lamps 335 and 336 that the subscribers have finished their conversation, she may release the connection by pressing the disconnect key 160. This closes, at contacts 163 of the key 160, a circuit for energizing the relay 81; and that relay in operating opens the previously traced circuit over which up to this time the relay 13 has been held energized. Relay 13 in releasing closes, by way of its right-hand armature and back contact and listening key sequence switch contact 410 (6 and 8), a circuit for energizing the motor magnet of the listening key sequence switch and causing that switch to return to its normal or 1 position,—the relay 95 having been released by the opening of its energizing circuit at the upper right-hand front contact and armature of relay 13.

During the continuance of the connection the relay 40 of the finder circuit has acted as a holding relay, the energizing circuit for this relay extending from battery by way of one or the other of the resistance coil branches completed at cam 408 of the listening key sequence switch, front contact and right-hand armature of relay 95, normally closed contacts 161 of the disconnect

key 160, conductor 88, contact terminal 25 and brush 21 of the selector switch CS, conductor 55, finder sequence switch contact 222 (17), left-hand winding of relay 40, finder sequence switch contact 219 (17), and right-hand winding of relay 40 to ground. This holding circuit is opened both directly by the opening of the contacts 161 of key 160 and indirectly by the release of relay 95. The holding relay 40 of the finder circuit therefore becomes inert and in releasing its armature closes a circuit that extends from battery through the motor magnet and contact 224 (17) of the finder sequence switch, back contact and armature of relay 40, finder sequence switch contact 223 (17), and inner back contact and right-hand armature of relay 42 to ground. This causes the finder sequence switch to move from position 17 to position 18. In position 18 a circuit is closed that extends from battery through the down-drive magnet 33 of the selector switch and finder sequence switch contact 209 (18) to ground. When the selector switch CS reaches its normal position as the result of the closure of this circuit, a circuit is closed that extends from battery through the motor magnet and contact 206 (18) of the finder sequence switch, and to ground by way of segment Y and the associated brush of the selector switch commutator. The closure of this circuit causes the finder sequence switch to move from position 18 to position 1, in which position it remains until its turn comes to be moved to position 2, where its associated line finder switch LF takes up the hunt for calling lines, as has already been described. The brushes of the line finder switch remain on the terminals of the line with which the connection had been established; but in position 1 of the finder sequence switch the brushes of one branch are disconnected at the finder sequence switch cams 227, 228, 229 and 210, and the brushes of the other branch are disconnected at the finder sequence switch cams 230, 231 and 232 and the outer lower front contact of relay 44. Upon pressing the disconnect key 160 the operator also removes the calling plug 334 from the spring jack 339 of the called subscriber's line, so that the circuits are all restored to their normal condition.

As has been observed, each finder circuit has two testing branches, one branch extending to the set of brushes 60, 61, 62, 63 and the other branch extending to the set of brushes 70, 71, 72, 73. Each of the branches is equipped with independently responsive testing appliances and as each of the two sets of brushes engages each of the sets of line terminals of the entire group in each rotation of the finder switch, every calling line has two chances in each rotation of the finder switch to appropriate the hunting

finder circuit. In the foregoing description of the operation of the system it has been assumed that the set of brushes comprising the brushes 60, 61, 62, 63, was the first to engage the terminals of the calling line A. It may now be assumed that the subscriber at station A takes his telephone receiver from its switchhook an instant after this set of brushes has passed over the contact terminals of the associated line; or that for some reason the testing apparatus associated with the branch leading to brushes 60, 61, 62, 63 has failed to respond. Consequently the finder switch continues to rotate and a few moments later, after an interval not exceeding half the period of rotation of the switch, the second set of brushes 70, 71, 72, 73 comes into engagement with the terminals of the calling line. In this case, as the brush 72 engages the contact terminal 58 a circuit is completed that extends from battery through the winding of relay 46, finder sequence switch contact 232 (2), conductor 16, brush 76 and its corresponding slip ring, brush 72, contact 58, conductor 7 associated with the calling line of station A and to ground by way of resistance coil 6. At the instant of engagement therefore the relay 46 is energized and closes a circuit that extends from battery through the left-hand winding of relay 41, inner armature and front contact of relay 46, finder sequence switch contact 231 (2), conductor 15, brush 75, and its corresponding slip ring, brush 71, terminal 57, thence by way of limb 2 of the calling subscriber's line through the substation apparatus and back by way of limb 1 of the line, terminal 56 of the line finder LF, brush 70, slip-ring and brush 74 of the line finder, conductor 14, finder sequence switch contact 230 (2), outer front contact and armature of relay 46 and to ground by way of the right-hand winding of relay 41. The relay 41 in operating closes a circuit that extends from battery in parallel branches through the motor magnet of the finder sequence switch 200 and the holding magnet 83 of the line finder switch, finder sequence switch contact 235 (2), left-hand winding of relay 43, sequence switch contact 233 (2), front contact and armature of relay 41, and inner back contact and left-hand armature of relay 42 to ground.

In the previously considered case where it was assumed that the brushes 60, 61, 62 and 63 were the first to engage the calling line terminals, the motor magnet of the finder sequence switch and the holding magnet of the finder switch were energized as the result of the engagement of the brushes with the terminals. In the present instance, the engagement of the brushes 70, 71, 72 and 73 with the calling line terminals causes the relay 43 to be energized in addition to the motor magnet and the finder switch holding

magnet 83. The relay 43 in operating closes a locking circuit for itself from battery by way of its right-hand winding, its inner front contact and armature, and finder sequence switch contact 209 (2 to 17) to ground. At its outer front contact and armature the relay 43 closes the energizing circuit of the relay 44, and the relay 44 prepares the finder circuit for extension to the brushes 70, 71, 72 and 73 which have found the calling line, instead of to the brushes 60, 61, 62 and 63, when the finder sequence switch, a moment later, moves out of its hunting position 2.

While the finder sequence switch is in position 2 and the finder switch is hunting, both branches of the finder circuit with their corresponding sets of brushes 60, 61, 62 and 63 and 70, 71, 72 and 73 are active, and the engagement of either set of brushes with the terminals of the calling line is instrumental in stopping the finder switch and moving the finder sequence switch out of position 2. It is possible that two lines whose terminals are diametrically opposite each other may be calling at the same time, in which case the test relays 40 and 45 associated with the brushes 60, 61, 62, 63 and the test relays 41 and 46 associated with the brushes 70, 71, 72 and 73 will be simultaneously energized. When this happens the energizing circuit for the motor magnet 80 of the finder switch is interrupted both at the back contact of relay 40 and at the back contact of relay 41, and the finder switch is stopped. The energizing circuit, including the motor magnet of the finder sequence switch 200 and the holding magnet 83 of the finder switch in parallel branches is also closed; but in this case it is closed by way of the path which includes the finder sequence switch contact 235 (2), the left-hand winding of relay 43, finder sequence switch contact 233 (2), and the front contact of relay 41, the path by way of the front contact and armature of relay 40 being open at the back contact of relay 41. Therefore relay 43 is operated and energizes relay 44, which switches the finder circuit from the branch extending to brushes 60, 61, 62, 63 to the branch extending to brushes 70, 71, 72, 73. Thus, where the two sets of brushes simultaneously encounter terminals of different calling lines the operation of the circuit is such as to give the brushes 70, 71, 72 and 73 the preference over the other set of brushes.

When the finder switch has been stopped with one or the other of its sets of brushes in engagement with the terminals of a calling line and the finder sequence switch has moved out of position 2, a circuit is closed that includes battery, windings of relay 41, finder sequence contacts 213 (3 to 16) and 214 (3 to 16), the upper armatures of relay 130

44 and either the back or front contacts of these armatures, depending upon which set of line finder switch brushes the circuit of the calling telephone line is being extended through, and over the conductors 9 and 10 or 14 and 15, as the case may be, and the associated brushes of the line finder switch to the circuit of the calling line. The relay 41 therefore is under the control of the telephone switchhook at the calling subscriber's station. If the calling subscriber hangs up at any time when the finder sequence switch is at a stage of its movement intermediate of its hunting stage 2 and its talking stage 17, the relay 41 is deenergized and a circuit is closed that extends from battery through the motor magnet and contact 234 (3 to 16) of the finder sequence switch, back contact and armature of relay 41, and inner left-hand back contact and armature of relay 42 to ground. Consequently the finder sequence switch moves from the intermediate stage in which it happens to be through position 16 and into position 17. In position 17 a circuit is closed for energizing the motor magnet of the finder sequence switch by way of sequence switch contact 224 (17), back contact and armature of relay 40, sequence switch contact 223 (17), and inner left-hand back contact and armature of relay 42 to ground. This moves the finder sequence switch into position 18, in which position a circuit is closed for energizing the sequence switch motor magnet by way of sequence switch contact 206 (18), and the Y segment and brush of the selector switch commutator to ground. This moves the finder sequence switch out of position 18 and into its normal or 1 position.

10 The foregoing is under the assumption that calling subscriber hangs up before the selector switch has completed its selection of the connecting circuit and the finder sequence switch has moved out of position 9. 45 If these acts have occurred and the calling line is extended to the connecting circuit at the time when the calling subscriber hangs up, then the finder sequence switch is moved to and rests in its talking position 17 until 50 the operator has pressed the disconnecting key 160 in response to the lighting of the calling subscriber's lamp 235, which results from the calling subscriber hanging up, when the movement of the finder sequence switch out of position 17 and the return of the selector switch are effected in the manner hereinbefore described.

In the system of this invention provision is made for automatically continuing the 60 test for an idle operator's position in case all of the positions are busy or otherwise unavailable when first tested by the selector switch. It will be remembered that the first stage of the upward movement of the selector switch is for the purpose of testing

the operator's positions, the movement of the switch being arrested when the test brush 48 engages the terminal 50 of the test wire leading to an available position. If no position is available at the time the test is made, the upward movement of the selector switch elevator continues until the test brush 48 has passed over all of the test terminals 50, at which time a grounded brush engages the segment H of the selector switch commutator 51. When this occurs a circuit is closed that extends from battery in parallel branches through the windings of the relays 42 and 47, finder sequence switch contact 207 (7), and selector switch commutator H and its corresponding brush to ground. Relay 42 in operating closes a locking circuit for itself and relay 47 by way of its inner right-hand front contact and armature, and finder sequence switch contact 203 (7 to 5) to ground. At its left-hand inner front contact and armature relay 42 closes a path, by way of finder sequence switch contact 205 (7 to 17), for energizing the finder sequence switch motor magnet. As a result the finder sequence switch moves out of position 7, interrupting at finder sequence switch contact 215 (7) the energizing circuit of the updrive magnet 34, which energizing circuit an instant before this has also been interrupted at the outer front contact and armature of relay 45 by the release of that relay as its locking circuit is broken by the passing of the test brush 48 beyond the last of the unavailable, and therefore grounded, operator's position test terminals 50.

When the finder sequence switch moves from position 7, as described, it continues to move until its energizing circuit, closed by the locking up of relay 42, is opened at finder sequence switch contact 205 (7 to 17). The finder sequence switch therefore comes to rest in position 18. In this position, as has already been described, the circuit of the down-drive magnet 33 is closed at finder sequence switch contact 209 (18); and when the selector switch reaches normal as the result of the closure of this circuit, the finder sequence switch is moved to position 1 as the result of the closure of its circuit at sequence switch contact 206 (218) and the Y segment of the selector switch commutator. In position 1 the circuit of the finder sequence switch motor magnet is again closed by way of the sequence switch contact 205 (1 to 3) and the inner front contact and armature of relay 42, which relay is still locked up by way of its inner right-hand front contact and armature, and sequence switch contact 203 (7 to 5). The finder sequence switch therefore is moved through position 3, and continues to move under the control of its cam 201 until it reaches and comes to rest in position 6. In position 6

the test relay 45 is locked up, the finder sequence switch is moved to position 7, and the selector switch elevator is again moved up to repeat the test for an available operator's position, in the manner which has already been described.

It will be noted that when the relay 42 is operated and locked up to bring about the rehunt for an available operator's position, 10 it disconnects ground from the conductor which extends to the back contact of its inner left-hand armature. This is for the purpose of preventing the passage of the finder sequence switch through position 2, 15 as it reestablishes the operator's hunting condition, from bringing about any change in the circuits already established. For instance, if it is assumed that the finder circuit is connected with the calling line by 20 way of the set of brushes 60, 61, 62 and 63, the relay 44 under these conditions being inert, and that the line with the terminals of which the brushes 70, 71, 72 and 73 are in engagement is now calling and has not 25 yet been connected with by another finder switch, then as the finder sequence switch passes through position 2 in reestablishing the operator's hunting condition the relay 41 associated with the brushes 70, 71, 72 30 and 73 is operated. If it were not for the disconnection of the ground at the inner left-hand back contact and armature of relay 42, the operation of relay 41 would close the circuit extending from battery in parallel branches through the motor magnet of the finder sequence switch and the holding magnet 83 of the finder switch, finder sequence switch contact 235 (2), left-hand winding of relay 43, finder sequence switch 35 contact 233 (2), front contact and armature of relay 41, and thence to ground at relay 42. The resultant operation of relay 43 would cause that relay to lock up and also close, at its outer front contact and armature, the energizing circuit for the relay 44. This would interrupt, at the contacts of relay 44, the connection assumed to exist 40 between the finder circuit and the calling line by way of the brushes 60, 61, 62 and 63 of the finder switch, and would switch the finder circuit to the other calling line with the terminals of which the brushes 70, 71, 72 and 73 are now assumed to be in engagement. Such action is prevented by the 45 interruption of the ground path at the inner left-hand back contact and armature of relay 42 when that relay is operated. This interruption of the path to ground at the inner left-hand back contact and armature of relay 42 also prevents the motor magnet of the finder switch from being energized to move the finder switch brushes off of the calling line terminals when both test 50 relays 40 and 41 are deenergized and their armatures refracted while the finder se-

quence switch is passing through position 2 in the rehunt operation.

The relay 42 is also arranged to control the advance starter wire circuit so as to prevent any interference with the functions of this circuit as the finder sequence switch moves through its cycle in reestablishing the operator's hunting condition. When the relay 42 operates, it opens at its outer left-hand back contact and armature the path 75 extending from the motor magnet of the finder sequence switch to finder sequence switch contact 202 (1). This is to prevent the ground applied at the finder sequence switch cam 201 as the sequence switch moves into and out of position 1 from being communicated by way of the 202 cam series 80 to the motor magnet of some other finder sequence switch that is standing in position 1 to move that sequence switch into position 85 2, thus causing the associated finder switch also to start hunting for calling lines. At its outer right-hand armature and back contact, the relay 42 opens the path extending from the 202 cam series to ground by way 90 of contact 203 (3 to 5) of the finder sequence switch that is repeating its cycle, in order to prevent the application of ground to that series to move some other finder sequence switch from its normal position 1 to its 95 hunting position 2. At its right-hand armature and front contact the relay 42 closes a short circuit of contact 202 (6 to 18) of the associated finder sequence switch in order to prevent the finder sequence switch 100 of the rehunting finder circuit from opening, as it passes from position 18 to position 6, the path over which ground is being applied by way of finder sequence switch contact 203² (3 to 5), for instance, of a finder 105 circuit that has just found a calling line to move the sequence switch of finder circuit F', for instance, out of its normal position 1 to cause it to take up the hunt for calling lines.

Relay 47, which is energized in parallel with the relay 42, in operating closes a short circuit about finder sequence switch contact 229 (3 to 17), another short circuit about finder sequence switch contact 232 (3 115 to 17), and another short circuit about finder sequence switch contact 211 (2 to 16). As the relay 47 is held energized by way of the locking contact of relay 42 and finder sequence switch contact 203 (7 to 5), these short circuits are maintained from the moment that the selector switch commutator segment H is grounded in position 7 of the finder sequence switch until the finder sequence switch has moved through its cycle 125 and out of position 5 in its repeated cycle of movement. The result of this is that while the finder sequence switch is repeating its cycle, current from the battery by way of resistance coil 93 continues to flow 130

to the test conductor 7 of the calling line by way of the test conductor of whichever branch of the finder circuit is in use for completing the connection. Consequently 5 the calling line is guarded and prevented from being connected with by another hunting finder switch during the repetition of the cycle.

The relay 47 in operating also closes, at 10 its inner upper front contact and armature, a branch to ground of the locking circuit for the relay 43, which maintains that relay operated when the other branch of the locking circuit is open at finder sequence switch 15 contact 209 (2 to 17) while the finder sequence switch is repeating its cycle. This holds the relay 43, and through it the relay 44, energized to continue the connection of the finder circuit with the set of brushes 70, 20 71, 72 and 73 in case it is that set through which connection has been completed with the calling line.

What is claimed is:

1. The combination with a group of telephone lines, of an extension circuit therefor having a plurality of branches, a testing device associated with each branch and responsive to the calling condition of any line, means for bringing said branches successively into connection with each of the lines of said group, and means under the control of each testing device for effecting the connection of said extension circuit with a calling line by way of the associated branch. 25

2. The combination with a group of lines, of an extension circuit therefor, a switch having contacts upon which said lines terminate and brushes with which said extension circuit is adapted to be connected, duplicate testing devices associated with said switch and responsive to the calling condition of any of said lines, means for bringing said testing devices separately into operative relation with each of said lines, and 40 means operated in the response of either of said testing devices for completing the connection of said extension circuit with a calling line. 45

3. The combination with a group of lines, of an extension circuit therefor, a plurality of testing devices associated with said extension circuit, means for bringing each of said testing devices successively under the control of each of the lines of said group, and means operated in the actuation of any 50 of said testing devices for completing the connection of said extension circuit with the line to which the testing device has responded.

4. The combination with a group of lines, of a common circuit therefor, said circuit having a plurality of branches each provided with a testing device responsive to an abnormal electrical condition of any of 55 the lines of said group, means for bringing

said branches successively into connection with each of the lines of said group, and means operated in the response of any of said testing devices to the abnormal electrical condition of a line with which it is 70 temporarily in connection for establishing a permanent connection of the aforesaid common circuit with said line by way of the associated branch.

5. The combination with a group of lines, 75 of means controlled by any line in calling for changing the electrical condition thereof, a finder switch having contacts upon which said lines terminate, means for moving said switch, duplicate testing devices 80 associated with said switch, said testing devices being responsive to the changed electrical condition of a tested line and being brought successively into connection with each of the lines of said group in the movement of said switch, and means actuated in the response of any of said testing devices for stopping said finder switch in engagement with the terminals of the calling line. 85

6. The combination with a group of lines, 90 and a common circuit therefor, of duplicate testing devices associated with said common circuit and responsive to the electrical condition of said lines, means for bringing said duplicate testing devices successively into 95 connection with each of the lines of said group, and means for completing the connection of said common circuit with a tested line upon the response of either of said testing devices. 100

7. The combination with a group of lines and a common circuit therefor, of duplicate testing devices associated with said common circuit and responsive to the electrical condition of said lines, means for bringing said 105 duplicate testing devices successively into connection with each of the lines of said group, and means for completing the connection of said common circuit with a tested line and rendering said devices inoperative 110 upon the response of either of said devices.

8. The combination with a group of lines and a common circuit therefor, of an automatic switch having contacts upon which said lines terminate and brushes to which 115 said common circuit is connected, means for moving said brushes over said contacts, duplicate testing devices associated with said common circuit and brought successively into connection with each of said lines in 120 the movement of said switch, said testing devices being responsive to an abnormal electrical condition of any of said lines, and means actuated in the operation of either of said testing devices for stopping the switch, 125 connecting the common circuit to the line to which the testing device has responded, and disconnecting the testing devices.

9. In a telephone system, a switch having a plurality of brushes and a series of con- 130

tact terminals common to said brushes, a group of telephone lines connected with said contact terminals, means for causing said brushes to move together over said series 5 and simultaneously engage different contact terminals thereof, and automatic means under the control of any of said lines for stopping the movement of said brushes when any one of them engages the terminal 10 of said line.

10. An automatic switch having a plurality of contact terminals arranged in a single bank, a plurality of brushes arranged to simultaneously engage different terminals 15 and to successively engage all of the terminals of said bank, a common circuit for said brushes, and selecting means for completing said circuit through either one of said brushes and the contact terminals with 20 which it is in engagement.

11. An automatic switch comprising a series of sets of contact terminals, a plurality of sets of brushes arranged simultaneously to engage different sets of contact terminals 25 and successively to engage all of said sets of contact terminals of the series, and electromagnetic mechanism under the joint control of either set of brushes and the set of terminals with which it is in engagement 30 for rendering that set of brushes electrically active and the other set electrically inactive.

12. An automatic switch having a series of contact terminals and a plurality of brushes each of which coöperates with all 35 of said contact terminals, a circuit common to said brushes, and means under the joint control of any of said brushes and any of the contact terminals which it engages for exclusively including that brush and the 40 associated contact terminal in said circuit.

13. The combination with a group of telephone lines, of a finder circuit therefor having a plurality of branches, an automatic switch having a series of contact terminals 45 with which the lines of said group are connected and a plurality of brushes with which said finder circuit branches are connected, each of said brushes being arranged to coöperate with all the contact terminals 50 of said series, means for moving said plurality of brushes simultaneously into engagement with a corresponding plurality of said contact terminals, and selecting means for exclusively completing the connection of 55 said finder circuit with a certain one of said brushes and the terminal with which it is in engagement.

14. The combination with a group of multiple brush switches, each switch of the 60 group having a single series of contact terminals arranged to be engaged successively by each of the brushes of the corresponding switch, of a group of lines multiplied to the contact terminals of said switches, a 65 group of extension circuits each having a

plurality of branches respectively connected with the brushes of the corresponding switch, means for causing the brushes of one of said switches to move continuously over the associated series of contact terminals, and 70 means actuated under the control of any one of said lines upon the engagement of one of the brushes of the rotating switch with the contact terminal of that line for stopping the rotation of said switch, exclusively 75 completing the connection of said extension circuit with the brush that is in engagement with said line, and starting the rotation of another of said switches.

15. The combination with a group of 80 lines, of an extension circuit therefor having a plurality of branches, means for closing said branches simultaneously to different lines and successively to all of the lines of said group, and means for opening all 85 but one of said branches.

16. The combination with a group of telephone lines, of an extension circuit therefor having a plurality of branches, means actuated by any of said lines in calling for 90 changing the electrical condition thereof, means for closing said branches simultaneously to different telephone lines and successively to all of the telephone lines of said group, and means responsive to the changed 95 electrical condition of any line for opening all the branches of said extension circuit excepting the branch closed to the line.

17. The combination with a switch having a plurality of contact terminals and a 100 plurality of brushes, of a group of telephone lines connected with said contact terminals, an extension circuit having branches connected with said brushes, means for moving said brushes together to bring each successively into engagement with all of the contact terminals of said switch and both simultaneously into engagement with different contact terminals, and means for stopping the movement of said brushes. 105

18. The combination with a switch having a plurality of contact terminals and a plurality of brushes, of a group of telephone lines connected with said contact terminals, an extension circuit having branches connected with said brushes, means for moving said brushes together to bring each successively into engagement with all of said contact terminals and both simultaneously into engagement with different contact terminals, means for stopping the movement of said brushes, and means for rendering inactive all but one of the branches of said extension circuit. 115

19. The combination with a group of telephone lines, of an extension circuit therefor having a plurality of branches, means actuated by any of said lines in calling for 125 changing the electrical condition thereof, a switch having a series of contacts upon 130

which the lines of said group terminate and a plurality of brushes upon which the branches of said extension circuit terminate, means for moving said brushes simultaneously into engagement with the contact terminals of different lines of said group and each brush successively into engagement with the terminals of all of the lines of said group, testing mechanism associated with 5 said extension circuit and responsive to the changed electrical condition of a calling line for stopping said switch when a brush engages a calling line terminal, and means controlled by said testing mechanism for 10 rendering inactive all but the branch terminating on the brush that has engaged the terminal of a calling line.

20. The combination with a group of telephone lines, of an extension circuit therefor having a plurality of branches, a switch having contacts upon which the lines of said group terminate and a plurality of brushes with which said branches of the extension circuit are connected, means actuated by any of said lines in calling for 25 changing the electrical condition thereof, means for causing said brushes to move simultaneously into engagement with different contacts and each brush successively into engagement with all of the contacts of the switch, a testing device associated with each branch of the circuit responsive to the changed electrical condition of a calling line, and means controlled in the actuation 30 of either of said testing devices for stopping the movement of said switch brushes and completing the connection of said extension circuit through the associated brushes and preventing its completion by way of another 35 of said branches.

40. The combination with a group of telephone lines, of an extension circuit therefor having a plurality of branches, an electromagnetic switch associated with said extension circuit for alternatively completing the connection of said circuit with one or another of said branches, a finder switch having a series of contacts upon which said telephone lines terminate and a plurality 45 of brushes with which said branches are respectively connected, means actuated by any line in calling for changing the electrical condition thereof, means for causing said brushes to move together to simultaneously 50 engage different contacts and each successively to engage all of the contacts of said series, testing means associated with said branches during the movement of said brushes and responsive to the changed electrical condition of a calling line, and means actuated in the response of said testing 55 means for stopping said switch brushes and controlling said electromagnetic switch to complete the connection of said extension 60 circuit with the branch associated with the

brush that has engaged the terminals of a calling line.

22. A selector switch having two series of contact terminals, means for moving said switch to test first one and then the other 70 of said series, means actuated in the test of the first series for controlling the movement of the switch to test the second series, and means made operative by the failure to operate of said test actuated means for causing said switch to repeat the test of said first series.

23. A selector switch having a plurality of banks of contact terminals and a corresponding plurality of brushes, means for 80 moving said switch, said movement being in two stages, means for selecting one of said brushes in the first stage of movement of said switch, means for causing the selected brush to select a contact terminal of the 85 corresponding bank in the second stage of movement, and means for preventing the second stage of movement made operative by the failure to select a brush in the first stage of movement. 90

24. A selector switch having a plurality of banks of contact terminals and a corresponding plurality of brushes, means for moving said switch, said movement being in two stages, means for selecting a particular 95 brush in the first stage of movement of said switch, means for causing the selected brush to select a contact terminal of the corresponding bank in the second stage of movement, means actuated by the selection of a 100 brush in the first stage of movement for causing the switch to proceed to its second stage, and means actuated upon the failure to select a brush in the first stage of movement for causing the switch to repeat the 105 first stage.

25. The combination with a calling line, of a plurality of operators' positions, each position being provided with a plurality of connecting circuits, means for selecting an 110 operator's position and then selecting a connecting circuit of said position and extending said calling line thereto, and means made operative by the failure of said selecting means to select an operator's position 115 for causing said means to repeat its operator-selecting operation.

26. A selector switch having two stages of movement, operators' positions adapted to be selected by said switch in its first stage 120 of movement, connecting circuits adapted to be selected by said switch in its second stage of movement, and means made operative by the failure of said switch to select an operator's position for preventing the movement 125 of said switch to its second stage and for causing the switch to repeat its first or operator-selecting stage.

27. The combination with a plurality of operators' positions each provided with con- 130

necting circuits, of a calling line, a selector switch, means for operating the same to select an available operator's position and then to select an idle connecting circuit 5 thereof and extend said calling line thereto, and means made operative by the unavailability of all of said operators' positions for causing said switch to repeat its position selecting operation and preventing it from 10 starting its connecting circuit selecting operation.

28. The combination with a plurality of operators' positions each having a plurality of connecting circuits, of a selector switch, 15 means for causing said switch to select an available operator's position in the first stage of its movement and to select an idle connecting circuit in the second stage of its movement, and means controlled by the un- 20 availability of all of said operators' positions for causing said switch to repeat the first stage of its movement and preventing it from entering into the second stage of its movement.

25 29. The combination with a plurality of operators' positions each provided with a plurality of connecting circuits, of a call-extending circuit, a selector switch having two stages of movement, means for selecting 30 an operator's position in the first stage of movement, means for selecting a connecting circuit of the selected position and extending said call-extending circuit thereto in the second stage of movement, means made 35 operative by the selection of an operator's position in the first stage for causing said selector switch to proceed to the second stage of its movement, and means made operative by the passage of said selector switch 40 through its first stage without selecting an operator's position for causing said switch to repeat its operator-selecting stage of movement.

30. A selector switch having a brush and 45 a series of contact terminals, means for causing said brush to move over and test said terminals, means actuated in the further movement of said switch for causing said brush to return and repeat its testing operation, a test circuit made operative by the 50 engagement of said brush with a predetermined terminal, means actuated in the operation of said test circuit for rendering inoperative said brush-returning and retesting means, and a second series of contact terminals tested by said switch in the continued 55 movement thereof.

31. The combination with a selector switch, of means for causing the same in the 60 initial stage of its movement to test for and select an available operator's position, and in its further movement to test for and select an idle connecting circuit of that position, mechanism operating at the end of the 65 initial movement to prevent the further

movement of the switch and cause it to repeat its initial movement, and means made operative by the selection of an operator's position in the initial movement of said switch for rendering inoperative the afore- 70 said mechanism.

32. The combination with a plurality of circuits divided into groups, of a common test circuit associated with each group, a selector switch, means for moving the same, 75 said switch being adapted to test the aforesaid test circuits in the initial stage of its movement and to test the circuits of a selected group in its further movement, controlling means made operative at the conclusion of the initial stage of movement of said switch for causing the switch to return and repeat its initial testing stage, and means responsive to a test circuit in the initial stage of movement for rendering inoperative 80 said controlling means.

33. The combination with a selector switch having a plurality of normally inactive brushes and a corresponding plurality of groups of contact terminals, of means for moving said switch, means for selecting and rendering active one of said brushes in the first stage of movement of said switch, means for causing the selected brush to select and connect with one of the contact terminals 95 of the corresponding group in the second stage of movement of said switch, and means made operative by the failure to select a brush in the first stage of movement for preventing said switch from proceeding to 100 its second stage and causing it to repeat its brush-selecting movement.

34. The combination with a group of telephone lines, of a group of operators' positions each provided with a plurality of connecting circuits, a finder circuit having two branches, means for establishing connection between said finder circuit and any calling line of said group over either of said branches, means for selecting an operator's 110 position and then extending said finder circuit to one of the connecting circuits thereof, and means made operative by the failure of said selecting means to select an operator's position for causing the same to repeat 115 its operator-selecting operation.

35. The combination with a group of telephone lines, of a plurality of operators' positions each provided with a plurality of connecting circuits, a finder circuit, a finder switch for establishing connection between said finder circuit and any one of said telephone lines, a selector switch for selecting an available operator's position and extending said finder circuit to an idle connecting 125 circuit thereof, duplicate testing apparatus and circuits controlling the connection of said finder circuit with a calling line of said group, and means made operative by the failure of said selector switch to select 130

an available operator's position for causing said switch to repeat its operator-selecting operation.

36. The combination with a group of telephone lines, of a group of operators' positions each provided with a plurality of connecting circuits, a finder circuit having a plurality of branches, a finder switch, means for operating the same to establish connection between said finder circuit and any calling line of said group over any of said branches, a selector switch, means for causing the same in the initial stage of its movement to test for and select an available operator's position, and in its further movement to test for and select an idle connecting circuit of that position, mechanism operating at the end of the initial movement to prevent the further movement of the switch 20 and cause it to repeat its initial movement, and means made operative by the selection of an operator's position in the initial movement of said switch for rendering inoperative the aforesaid mechanism.

37. In a telephone system, the combination with a group of lines, of a plurality of operators' positions each provided with a plurality of connecting circuits, a finder circuit having a plurality of branches, a finder switch having contacts upon which said lines terminate and brushes with which said finder

circuit branches are connected, a testing device associated with each branch and responsive to the calling condition of any line, means for bringing said branches successively into connection with each of the lines of said group, means under the control of each testing device for effecting the connection of said finder circuit with a calling line by way of the associated branch, a selector 40 switch having a plurality of normally inactive brushes with which said finder circuit is connected and a corresponding plurality of groups of contact terminals to which the connecting circuits of corresponding operators' positions extend, means for moving said switch, means for selecting and rendering active one of said brushes in the first stage of movement of said switch, means for causing the selected brush to select and connect with one of the contact terminals of the corresponding group in the second stage of movement of said switch, and means made operative by failure of said switch to select a brush in the first stage of movement for 50 preventing said switch from proceeding to its second stage and causing it to repeat its brush-selecting movement.

In witness whereof, I hereunto subscribe my name this 6th day of August, A. D. 1918. 60

SAMUEL B. WILLIAMS, JR.
